UNITED STATES PATENT OFFICE

95,809

DESIGN FOR A SHOE

Vincent De Liso, Astoria, N. Y.

Application April 16, 1935, Serial No. 56,410

Term of patent 3½ years

To whom it may concern:

Be it known that I, Vincent De Liso, a citizen of the United States, residing in Astoria, Long Island, N. Y., have invented a new, original, and ornamental Design for a Shoe, of which the following is a specification, reference being had to the accompanying drawing, forming part thereof.

I claim:

The ornamental design for a shoe, as shown.

VINCENT DE LISO.
